CONVEYER

Francis Hogg, Wesleyville, Pa., assignor to The Standard Stoker Company, Incorporated, a corporation of Delaware

Application December 31, 1935, Serial No. 56,874

6 Claims. (Cl. 83—52)

This invention relates to conveyers in general but more particularly to fuel conveyers for use in stokers for conveying fuel such as coal of mixed sizes from a source of supply and delivering it to a furnace.

The object of the invention is to provide a conveyer including a fuel crusher and means for by-passing around the crusher fuel of a predetermined size, or, otherwise expressing it, fuel already of a size suitable for delivery to the furnace.

Other objects and the advantages of the invention will be apparent from the following description and the accompanying drawing, in which,

Fig. 1 is a central vertical longitudinal section through the conveyer of the invention;

Fig. 2 is a vertical transverse section through the conveyer taken rearward of the crusher in the line 2—2 of Fig. 1; and

Fig. 3 is a similar section taken forward of the crusher on the line 3—3 of Fig. 1.

For purposes of description the conveyer A of the invention is shown in position on a locomotive tender 10 for transferring fuel from the fuel bin 11 thereof forwardly to the locomotive furnace (not shown). The tender is of conventional form having the plates 12 in the floor of the fuel bin 11 slidable, as well known in the art, to create a shiftable opening 13 through which the fuel gravitates into the conveyer A.

The conveyer A comprises a conduit 14 consisting of a trough section 15 disposed beneath the slide plates 12 to receive fuel from the fuel bin 11 through the shiftable opening 13 and a tubular section 16 in axial alignment with the trough section and extending forwardly therefrom toward the locomotive. A screw 17 rotatable in the conduit advances the fuel through the trough section and into and through the tubular section. At the junction of these sections a fuel crusher 20 is suitably mounted at one side of the screw 17. This crusher cooperates with the screw to break down or crush the larger lumps of fuel being advanced by the screw into the tubular section 16.

Rearward of and adjacent to the crusher 20, the trough section 15 is apertured in its floor at 21. The apertured floor in effect constitutes a grid or riddle permitting fuel of a predetermined size or the fuel already of a size suitable for delivery to the furnace to pass through and to retain in the trough section fuel of a size larger than the apertures or openings 21.

55 A casing 22 rigid with the conduit 14 receives

the fuel that falls through the openings 21. The casing is disposed lengthwise of the conduit and extends from the rear end of the elongated openings 21 of the trough section to the opening 23 in the bottom side of the tubular section forward of the crusher 20. A screw 24 rotatable in the casing 22 advances the fuel therein forwardly to and upwardly through the opening 23 into the tubular section 16 where it is carried forward by the screw 17. Thus the fuel from the bin 11 already of a size suitable for delivery to the furnace is by-passed around the crusher 20 and therefore such fuel is not subjected to the cooperative crushing action of the crusher and the screw 17.

Any suitable drive mechanism may be employed for driving the screws 17 and 24 from their rearward ends including the gearing 25 and a clutch 26 shiftable to render the screw 24 inoperative during operation of the screw 17.

Those familiar with stokers will recognize that by-passing fuel already of a suitable size for delivery to the furnace from the trough section of the conduit around the crusher into the tubular section of the conduit decreases the undesirable breakdown or crushing of such fuel.

I claim:

1. In a conveyer for transferring fuel of mixed sizes from a source of supply, the combination of a conduit, a screw rotatable in the conduit for advancing fuel therethrough, a crusher in said conduit intermediate the ends thereof disposed at a side of said screw, said conduit having an opening in its floor rearward of said crusher permitting fuel of a size smaller than the opening to pass therethrough and retaining in the conduit fuel of a size larger than the opening, said screw and crusher cooperating to crush the fuel retained in the conduit, and means beneath said opening receiving the fuel passing therethrough and by-passing the same around said crusher and delivering such fuel into the conduit forward of the crusher.

2. In a conveyer for transferring fuel of mixed sizes from a source of supply, the combination of a conduit, a screw rotatable in the conduit for advancing fuel therethrough, a crusher in said conduit intermediate the ends thereof disposed at a side of said screw, said conduit having an opening in its floor rearward of said crusher permitting fuel of a size smaller than the opening to pass therethrough and retaining in the conduit fuel of a size larger than the opening, said screw and crusher cooperating to crush the fuel retained in the conduit, and a screw conveyer

beneath said opening receiving the fuel passing therethrough and by-passing the same around said crusher and delivering such fuel into the conduit forward of the crusher.

- 5 3. In a conveyer for transferring fuel of mixed sizes from a source of supply, the combination of a conduit, a screw rotatable in the conduit for advancing fuel therethrough, a crusher in said conduit intermediate the ends thereof disposed at a side of said screw, said conduit having an opening in its floor rearward of said crusher permitting fuel of a size smaller than the opening to pass therethrough and retaining in the conduit fuel of a size larger than the opening, said screw and crusher cooperating to crush the fuel retained in the conduit, and a screw conveyer beneath said opening receiving the fuel passing therethrough and by-passing the same around said crusher and delivering such fuel into the conduit forward of the crusher, said screw conveyer comprising a casing secured to said conduit and a screw rotatable in said casing.
- 10 4. In a conveyer for transferring fuel of mixed sizes from a source of supply, the combination of a conduit, a screw rotatable in the conduit for advancing fuel therethrough, a crusher in said conduit intermediate the ends thereof disposed at a side of said screw, said conduit having an opening in its floor rearward of said crusher permitting fuel of a size smaller than the opening to pass therethrough and retaining in the conduit fuel of a size larger than the opening, said screw and crusher cooperating to crush the fuel retained in the conduit, and a screw conveyer beneath said opening receiving the fuel passing therethrough and by-passing the same around said crusher and delivering such fuel into the conduit forward of the crusher, said screw conveyer comprising a casing secured to said conduit and a screw rotatable in said casing, and driving mechanism for said screws including a clutch

shiftable to render the second named screw inoperative during operation of the first named screw.

5 5. In a conveyer for transferring fuel of mixed sizes from a source of supply, the combination of a conduit, a screw rotatable in the conduit for advancing fuel therethrough, a crusher in said conduit intermediate the ends thereof disposed at a side of said screw, said conduit having an opening in its floor rearward of said crusher 10 permitting fuel of a size smaller than the opening to pass therethrough and retaining in the conduit fuel of a size larger than the opening, said screw and crusher cooperating to crush the fuel retained in the conduit, means beneath said 15 opening receiving the fuel passing therethrough and bypassing the same around said crusher and delivering such fuel into the conduit forward of the crusher, and means rendering the aforesaid means inoperative during operation of said 20 screw.

6. In a conveyer for transferring fuel of mixed sizes from a source of supply, the combination of a conduit comprising a trough section and a tubular section in axial alignment, a screw rotatable in the conduit for advancing fuel through the trough section into and through the tubular section, a crusher in said conduit at the junction of said sections at a side of said screw, said trough section having an opening in its floor rearward 25 of said crusher permitting fuel of a size smaller than the opening to pass therethrough and retaining in the trough section fuel of a size larger than the opening, said screw and crusher cooperating to crush the fuel retained in the trough section, and means beneath said opening receiving the fuel passing therethrough and bypassing the same around said crusher and delivering such fuel into said tubular section forward of the crusher. 30 35
